(57) **CLAIM**

The ornamental design for a turbocharger inlet pipe as shown and described.

DESCRIPTION

FIG. 1 is a perspective view of the turbocharger inlet pipe.

FIG. 2 is a front view of the turbocharger inlet pipe.

FIG. 3 is a back view of the turbocharger inlet pipe.

FIG. 4 is a left side view of the turbocharger inlet pipe.

FIG. 5 is a right side view of the turbocharger inlet pipe.

FIG. 6 is a top view of the turbocharger inlet pipe.

FIG. 7 is a bottom view of the turbocharger inlet pipe.

FIG. 8 is an orthographic view of the turbocharger inlet pipe; and,

FIG. 9 is an exploded view of the turbocharger inlet pipe. In the drawings, the broken lines depict portions of the turbocharger inlet pipe that form no part of the claimed design.

1 Claim, 9 Drawing Sheets
